(57) **CLAIM**

The ornamental design for a portable tool bag, as shown and described.

DESCRIPTION

The nature and intended use of the article being an ornamental design to permit tools to be carried while allowing the use of both hands.

FIG. 1 is a front elevational view of the portable tool bag of the present invention;

FIG. 2 is a rear elevational view of the portable tool bag of FIG. 1;

FIG. 3 is a left side elevational view of the portable tool bag of FIG. 1;

FIG. 4 is a right side elevational view of the portable tool bag of FIG. 1;

FIG. 5 is a top plan view of the portable tool bag of FIG. 1;

FIG. 6 is a bottom plan view of the portable tool bag of FIG. 1; and,

FIG. 7 is a top, front, right side perspective view of the portable tool bag, wherein the cover is shown in an alternate position.
